UNITED STATES PATENT OFFICE.

OSCAR M. BERGSTROM, OF MINNEAPOLIS, MINNESOTA.

GEARING.

1,137,735.

Specification of Letters Patent.

Patented May 4, 1915.

Application filed February 1, 1912. Serial No. 674,808.

To all whom it may concern:

Be it known that I, OSCAR M. BERGSTROM, a citizen of the United States, residing at Minneapolis, in the county of Hennepin and State of Minnesota, have invented certain new and useful Improvements in Gearing; and I do hereby declare the following to be a full, clear, and exact description of the invention, such as will enable others skilled 10 in the art to which it appertains to make and use the same.

My invention has for its object to provide a simple and highly efficient air pump adapted to remain permanently applied to 15 an automobile, to be driven from the engine thereof, and to be thrown into and out of action, at will, while the machine is at a stand still, and while the transmission mechanism is disconnected from the traction 20 wheels.

To the above ends, the invention consists of the novel devices and combinations of devices hereinafter described and defined in the claims.

Any suitable type of air pump may be employed so far as my present invention is concerned, but for illustration, I have shown an air pump of the general type disclosed in my prior Patent No. 968,732, of date, August 25 30th, 1910, entitled "pumping attachment for automobiles." The pump arrangement disclosed in my said prior patent required one of the traction wheels to be jacked up, or lifted from the ground, and then driven, 35 in order to operate the pump, and the pump was detachably applied to the hub of said traction wheel. My present arrangement enables the pump to remain permanently applied to the machine and by a novel device, I provide an extremely simple and efficient means for throwing the pump into and 40 out of action, at will, as required to inflate the tires of the machine. Also the arrangement is such that when the pump is thrown 45 into action, it will be driven either from the engine crank shaft or from a part that is driven from the engine crank shaft while the traction wheels of the machine are idle or disconnected from the transmission mechanism. In the illustration shown in the 50 drawings, a gear for driving the pump is connected to that portion of the transmission

shaft which is between the engine crank shaft proper and the differential gear mechanism and which is, therefore, driven whenever the engine is in action and without requiring the traction wheels to be driven. 55

In the accompanying drawings which illustrate the invention, like characters indicate like parts throughout the several 60 views.

Referring to the drawings, Figure 1 is a plan view showing the pump, a portion of the machine frame, a portion of the transmission shaft, and the improved connections 65 for driving the pump from the transmission shaft, some parts being broken away, and some parts being sectioned; Fig. 2 is a section taken on the line $x^2 x^2$ on Fig. 1, some parts being broken away and showing also 70 a portion of the floor of the vehicle body; Fig. 3 is a vertical section taken on the line $x^3 x^3$ on Fig. 2; Fig. 4 is a front elevation of the parts shown in Fig. 3, portions being broken away; Fig. 5 is a view in rear elevation 75 illustrating a modified arrangement for throwing the pump into and out of action, some parts being broken away and some parts being indicated by dotted lines only; and Fig. 6 is a view of the parts shown in 80 Fig. 5, partly in side elevation and partly in vertical section.

Of the parts of the machine or automobile, the numeral 1 indicates the running gear frame, the numeral 2 indicates a transmission shaft, and the numeral 3 the floor of the machine body. 85

The gear 4 for driving the air pump is, as shown, a diametrically split gear, the sections of which are clamped to a sleeve 5, 90 which latter, as shown, is rigidly secured to and carried by the transmission shaft 2.

The pump shown comprises two axially aligned opposing cylinders 7 secured to a central crank shaft casing 8. The crank shaft casing 8, on one side, is rigidly secured, as shown, by a nutted bolt 9, to the intermediate portion of a shipper lever 10. This shipper lever 10, as shown, at its upper end is pivotally connected by a nut-equipped bolt 100 11, to a supporting bracket 12 which, in turn, is riveted, or otherwise rigidly secured to the adjacent bar of the running gear frame 1.

The pistons of the pump are driven

through a suitable crank rod from a spur gear 13 that operates as a crank disk, and, as shown, has a hub projecting into the crank shaft casing 8, and journaled therein by means of a suitable ball bearing 14. By oscillatory movements of the so-called shipper lever 10, the gear 13 is adapted to be moved into and out of mesh with the driving gear 4 on the transmission shaft 2. The 10 novel device for throwing the said gears into and out of mesh, may take different forms, but is preferably constructed, as illustrated in Figs. 1 to 4 inclusive, wherein the numeral 15 indicates a clamping arm provided with 15 a shallow hub that works in a segmental slot 16 formed in the lower extremity of the lever 10. The hub of the arm 15 has threaded engagement with the threaded shank of a clamping bolt 17 that is rotatably mounted on the lower end of the bearing bracket 12, and at its front end is provided with a flanged head 18. This flanged head 18 is provided with circumferentially spaced perforations 19. A set screw 20 is passed 20 through one or the other of the perforations 19 and is screwed into the lower end of the bracket 12. By proper rotary adjustment of the clamping bolt 17, the clamping lever 15 may be so adjusted that when it is forced 25 downward, as shown in Fig. 2, it will clamp the free end of the shipper lever 10 against the bracket 12 with sufficient friction to hold the driven gear 13 in mesh with the driving gear 4.

30 An operating rod 21 is pivotally connected at its lower end to the free end of the clamping arm 15 and is passed upward through the perforated lug 22 formed on an upwardly extended arm of the shipper lever 10. The upper end of this rod 21 is passed upward through a slot 23 in the floor 3 and is provided with a suitable hand piece 24.

35 When the rod 21 is pulled upward to raise the clamping arm 15, the latter will release its bite on the shipper arm 10, and then by pulling laterally on the upper end of the rod 21, the shipper lever 10 may be oscillated on its pivoted bolt 11, so as to throw the 40 gear 13 out of mesh with the gear 4. When the clamping arm 15 is released, as above stated, the gear 13 may be moved into mesh with the gear 4 by pushing or pressing the raised upper end of the rod 21 toward the 45 right in respect to Fig. 2. When the gear 13 is thrown out of mesh with the gear 4, the shipper lever 10 may be secured in its retracted position by pressing the clamping arm 15 downward, while at the same time 50 holding the upper end of the rod 21 down or pressed toward the left, in respect to Fig. 2. Hence, by the clamping arm 15, the shipper lever 10 may be frictionally secured to either one of the two extreme positions

above noted, so that the gear 13 may, at will, 65 be held in mesh with the gear 4, or secured out of mesh therewith.

In practice, I have found that sometimes the operator will step on the head of the operating rod 21 and thereby set the clamping lever 15 so tightly that it is very difficult to release the same by hand or by again pulling upward on the said rod. To prevent this extreme setting of the clamping lever, I (see Fig. 1) provide the shipper lever 10 75 with a laterally projecting lug 25 that is adapted to engage a stop screw 26 screwed through a lug 27 on the bearing bracket 12.

The clamping lever 15 is adapted to be given approximately a constant extreme 80 movement under manipulation through the operating rod 21, and hence, to vary the tension under which the said clamping lever will be frictionally set, I have made the clamping bolt 17 rotatably adjustable. Obviously, the further the threaded end of the bolt 17 is screwed into the hub of the clamping lever 15, the greater will be the clamping 85 action of said lever when forced to its extreme downward position shown in Fig. 2. 90

In the modified form of the device shown in Figs. 5 and 6, the crank shaft casing 8 is provided with an axially projecting threaded trunnion 28 that projects through a vertical slot 29 in a bifurcated supporting 95 bracket 30, and is engaged by the threaded hub 31 of the hand operated clamping lever 32. With this construction, when the pump is lowered, as shown, the gear 13 will be thrown into mesh with the gear 4, and the 100 said pump may be secured in such position by tightening the clamping lever 32 on the bracket 30. When the clamping lever 32 is loosened on the bracket 30, it may be adapted to raise or lower the pump so as to throw the 105 gear 13 either into or out of mesh with the gear 4. By tightening the said clamping lever on the said bracket when the pump is raised, the gear 13 may be secured out of mesh with the gear 4. 110

What I claim is:

1. The combination with a driving gear, of a movable gear support, a driven gear on said support, said support being movably mounted and arranged to throw said two 115 gears into and out of mesh, a clamp operative to secure said support in one position or another, and a common operating rod or element connected to said support and to said clamp and movable in one direction to 120 move the former and in another direction to operate the latter.

2. The combination with a driving gear and a movable gear support, of a shipper lever pivoted to said support and having a 125 segmental slot, a driven gear carried by said shipper lever, a clamping bolt anchored to said support and projecting through the slot

in said shipper lever, a clamping arm having threaded engagement with said bolt and coöperating therewith to clamp said shipper lever in respect to said support, and an operating rod pivotally connected to said clamping lever and passed through a guide on said shipper lever, the said rod, when moved endwise, serving to set or release said clamping arms, and when moved laterally,

to oscillate said shipper lever and thereby 10 throw said driven gear into or out of mesh with said driving gear.

In testimony whereof I affix my signature in presence of two witnesses.

OSCAR M. BERGSTROM.
